US00D878533S

(12) **United States Design Patent** (10) Patent No.: **US D878,533 S**
(45) Date of Patent: **** Mar. 17, 2020**

(54) **FILTRATION UNITS**

(71) Applicant: **KAY GUNTHER GABRIEL**, Cottbus (DE)
(72) Inventors: **Kay Gunther Gabriel**, Cottbus (DE);
Gabriele Terbahl, Saarbrücken (DE);
Martin Kaschek, St. Ingbert (DE)

(**) Term: **15 Years**

(21) Appl. No.: **35/505,469**

(22) Filed: **Jan. 10, 2018**

(80) **Hague Agreement Data**

Int. Filing Date: **Jan. 10, 2018**

Int. Reg. No.: **DM/102059**

Int. Reg. Date: **Jan. 10, 2018**

Int. Reg. Pub. Date: **Aug. 10, 2018**

Primary Examiner — Khawaja Anwar

(57) **CLAIM**

The ornamental design for filtration units, as shown and described.

DESCRIPTION

1.1 : Perspective
1.2 : Bottom
1.3 : Top
1.4 : Front
1.5 : Back
1.6 : Left
1.7 : Right
2.1 : Perspective
2.2 : Bottom
2.3 : Top
2.4 : Front
2.5 : Back
2.6 : Left
2.7 : Right

The broken lines illustrating portions of the filtration units form no part of the claimed design.
